CLAIM

The ornamental design for a dispenser cap with integrated handle, as shown and described.

DESCRIPTION

FIG. 1 is a perspective view illustrating a dispenser cap with integrated handle of the present invention;

FIG. 2 is a top view illustrating the dispenser cap with integrated handle;

FIG. 3 is a right side view of the dispenser cap with integrated handle with the left side view being a mirror image thereof;

FIG. 4 is a front view of the dispenser cap with integrated handle shown in FIG. 1;

FIG. 5 is a back view of the dispenser cap with integrated handle; and,

FIG. 6 is a bottom view of the dispenser cap with integrated handle shown in FIG. 1.

The broken lines shown in the drawing Figures are meant to illustrate the environment of the present invention and form no part of the claimed design.
